UNITED STATES PATENT OFFICE.

AARON H. WOLFF, OF NEW YORK, N. Y.

DESIGN FOR A GAS-STOVE.

SPECIFICATION forming part of Design No. 25,284, dated March 24, 1896.

Application filed October 7, 1895. Serial No. 564,951. Term of patent 7 years.

To all whom it may concern:

Be it known that I, AARON H. WOLFF, a citizen of the United States, residing at New York, in the county and State of New York, 5 have invented and produced a new and original Design for Gas-Stoves, of which the following is a specification, reference being had to the accompanying drawing, in which I have represented my design by a perspective view showing the front and side elevations.

The leading features of my design consist in the ornamental side columns and end leaflet ornaments of the open-front frame, the ornamental open-work panel and medallion 5 of the upper front frame, the ornamental balcony and the ornamental canopy, and the paneled side frames.

The design of the open-front frame A comprises the ornamental side columns *a a'* in imitation of rope with thimble ends and end 5 diverging leaflet ornaments *b b' b² b³* and the ornamental feet *c c'* with claw-bases, and a molded edge *d* extends along the top edge of the front frame, A.

The design of the upper front frame, B, comprises the ornamental open-work panel *e* of curved bars with groups of scroll, leaflet, and shell ornaments in relief and a center medallion with figures in relief.

The design of the balcony C comprises the nearly-semielliptical molded outline and the ornamental open-work fender *h*, having straight edges adjacent to the lower ends of the columns *a a'*, a contracted base curved in outline against the open front frame with radially-ribbed ornaments *g* in relief adjacent to the leaflet ornaments *b² b³*, and a pointed end.

The design of the canopy D comprises the nearly-semielliptical outline with contracted top portion curved in outline against the open-front frame with radially-ribbed ornaments *i* in relief and the molded center *l* adjacent to the leaflet ornaments *b b'*, the molded semi-elliptical face *m* with recessed ornaments, and the leaflet corner-brackets *o* in relief adjacent 45 to the upper ends of the columns *a a'*.

The design of the lowerside frames, E, comprises the rectangular panels *r r'* with smooth-grained surfaces. The design of the upper side frames, F, comprises the rectangular 50 panel S, with smooth-grained surface.

What I claim is—

1. The design for a gas-stove substantially as shown and described.
2. In the design for a gas-stove, the open-front frame, substantially as shown and described.
3. In the design for a gas-stove the open-work and ornamental panel *e* of the upper front frame, substantially as shown and described.
4. In the design for a gas-stove, the balcony, substantially as shown and described.
5. In the design for a gas-stove the canopy, substantially as shown and described.
6. In the design for a gas-stove the side-paneled frame, substantially as shown and described.

Signed by me this 4th day of October, A. D. 1895.

AARON H. WOLFF.
